US00D946047S

(12) **United States Design Patent** (10) Patent No.: **US D946,047 S**
(45) Date of Patent: ** *Mar. 15, 2022

(54) **DISPLAY SCREEN WITH GRAPHICAL USER INTERFACE**

(71) Applicant: **Google LLC**, Mountain View, CA (US)

(72) Inventors: **Rachel Inman**, San Francisco, CA (US); **Jeremy Edelblut**, Sunnyvale, CA (US); **Marek Gorecki**, Los Gatos, CA (US); **Joost Korngold**, Sunnyvale, CA (US)

(73) Assignee: **GOOGLE LLC**, Mountain View, CA (US)

(*) Notice: This patent is subject to a terminal disclaimer.

(**) Term: **15 Years**

(21) Appl. No.: **29/738,399**

(22) Filed: **Jun. 17, 2020**

Related U.S. Application Data

(63) Continuation of application No. 29/703,016, filed on Aug. 23, 2019, now Pat. No. Des. 890,811, which is a continuation of application No. 29/646,664, filed on May 7, 2018, now Pat. No. Des. 891,465.

CLAIM

The ornamental design for a display screen with graphical user interface, as shown and described.

DESCRIPTION

The sole FIGURE is a front view of a display screen with graphical user interface, showing the new design.

The broken lines of uneven length show the display screen and form no part of the claimed design.

1 Claim, 1 Drawing Sheet
